UNITED STATES PATENT OFFICE.

JOHN BERGSTEN, OF REDONDO BEACH, CALIFORNIA, ASSIGNOR OF ONE-HALF TO N. W. HENDERSHOT, OF LOMITA, CALIFORNIA.

COMBINED CASING-HEAD PACKER AND BLOW-OUT PREVENTER.

Application filed October 27, 1924. Serial No. 745,974.

- This invention relates to combination casing head packers and blow-out preventers, and has for an object a device of this character which has a three-fold purpose, in that it will sustain the weight of tubing or casing, securely prevent gas, oil or other liquid escape past the casing head, and allow for a pressure relief of such gas, oil or other liquid.
- 10 The invention has for a further object the provision of a device which will allow tubing to be passed through the same and yet will secure the tubing in any desired position relative to the same.
- 15 With the above and other objects in view, including inexpensiveness of construction, ease of operation, durability and serviceability, the invention consists in the novel and useful provision, formation, construction, association and relative arrangement of parts, members and features, all as shown in one embodiment in the accompanying drawing, described generally, and more particularly pointed out in claims.
- 20 In the drawing:
- Figure 1 is a fragmentary side elevation showing the improved device in cooperation with strings of casing;
- Figure 2 is a fragmentary enlarged, partly sectioned plan view of the device;
- 30 Figure 3 is a fragmentary cross sectional view on the line 3—3 of Figure 2; and
- Figure 4 is a fragmentary cross sectional view of certain operative means for compressing packing in the device.
- Corresponding parts in all the figures are designated by the same reference characters.
- Referring with particularity to the drawing, the improved device is designated as an 40 entirety and in one embodiment by A, and such device includes among its elements a spider a, a casing head member b, and a blow-out preventer c. The spider a may be substantially annular in form and have a screw-threaded engagement with the casing head member, as shown at 1, the said spider to this end being formed with a base portion 2 having an annular outer flange 3 which is screw-threaded and with an outstanding rim portion 4. An inner annular flange or wall 5 joins the base 2, and the inner annular wall thereof diverges upwardly from the base as shown at 6 so that slip members 7 may be accommodated therein, said slips being conventional in form, that is, wedge-shaped, and the diverging wall tends to seat the slips tightly against tubing such as shown at 8 to hold such tubing in a given position relative to the spider. Said spider is provided with one or more annular 60 grooves on the base thereof as shown at 9 and 10, and such annual grooves are adapted to accommodate annular packing rings 11. The casing head b comprises a base member 12, substantially annular in 65 form with a central annular flange 13 which is provided with a taper screw thread 14 whereby a casing 15 may be secured thereto, said base member being formed with one or more annular grooves as shown at 16 and 17 70 within which may be received annular gaskets 18, and said casing head is likewise provided with a flange 19. This flange 19 is annular in form where it has a screw-threaded engagement with the spider, as 75 shown at 1, and it is likewise provided with two diametrically opposed, substantially parallel and straight-sided portions as shown at 20 and 21. Curved side portions 22 and 23 are joined with such side portions 20 and 80 21. The blow-out preventer c is interposed within the confines of the flange 19 and between the bases 2 and 12 of the members a and b.
- The said blow-out preventer c comprises 85 in the embodiment shown upper and lower substantially annular split discs 24, 25, 26 and 27, and which discs are provided with peripheral flanges as shown for the upper discs at 28 and the lower discs at 29. The 90 upper and lower discs are enlarged adjacent the inner curved surfaces thereof at 30 and 31, and are channeled as shown at 32 so as to receive split gasket members 33. Adapted to be interposed between the upper and 95 lower discs is packing means d forming a part of the blow-out preventer c, and this packing means may comprise flexible members 34 and 35 formed of rubber composition or other material. Such members are 100 substantially annular in part and provided with two diametrically opposed extensions or wings as shown at 36 and 37, and such parts 34 and 35 are likewise provided with peripheral grooves as shown at 38 and 39. 105 The top and bottom disc members are provided with diametrically disposed slotted portions designated generally as 40, and when the packing means d is compressed it is forced through such slotted portions 40 of 110

the discs and against the gaskets 9 and 10, as well as other portions of the base parts 2 and 12 respectively of the spider and casing head members. Compressors designated generally by *e*, of which there are two, in the showing, are adapted to be received within the grooved portions of the packing means *d* and such compressors may comprise split rings formed with diametrically disposed head portions as shown at 41, which head portions are guided when moved by the flat side portions 20 and 21 in the casing head. It will also be noted that the extensions 36 and 37 of the packing are received between the head portions 41. Means *f* is provided for causing inward or outward movement of the compressor members *e* so as to compress the packing *d* against the periphery of the tubing or casing 8. Of such means *f* there are two complete members diametrically disposed with relation to the casing head and only one of such complete members will be described, it being understood that the other is identical in form. The means *f* includes a member 42 which has a screw-threaded engagement with the casing head, as shown at 43, and such member is substantially annular in form and screw-threaded internally as shown at 44. Said member 42 is likewise stepped and of greater diameter than the internal diameter of the screw-threaded part 44, as shown at 45 so as to receive packing 46 which is held in position by a flange member 47 which is bolted to the member 42. Carried within the member 42 is an annular member 48 which is screw-threaded at 49 for engagement with the screw-threaded part 44 and such member 48 is formed with a longitudinal key-way 50, and a gear 51 is carried upon such member 48 and has a part 52 received in said key-way 50. A long pin 53 is passed through the member 48 and has a screw-threaded engagement with the compressor member *e* as shown at 54. A standard 55 carries a part 56 adapted to bear against an end of the pin 53 as illustrated at 57, and a shaft 58 is suitably supported above the spider by brackets 59 and 60, and such shaft carries a gear 61. A further bracket 62 is adapted to carry a shaft 63 to which shaft is joined a crank arm 64 and such shaft 63 carries a gear 65 adapted to mesh with the gear 61. Said shaft likewise carries a gear illustrated at 66 and a chain or other medium 66^a is passed over the gears 51 and 66. The shaft 58 likewise carries a gear as shown at 67 and a chain 68 is adapted to be passed over such gear 67 and a gear 51 on the means *f* on the side 69 of such device, it being understood that the means *f* on the side 70 has just been described. Thus a turning of the crank arm will rotate the members 48 and either cause an inward travel of such members to force the com-

pressors against the packing *d*, which will force such packing around the periphery of the tubing 8, and outward through the slots 40 in the upper and lower discs or a reverse turning will loosen such packing from such 70 position.

The arrangement shown allows the packing *d* to be firmly compressed about the tubing. The flange 13 is likewise provided with an opening 71 for reception of a pipe 72 for 75 the purpose of carrying away excessive pressure, whether fluid or gaseous, from between the casing 15 and the tubing 8. The arrangement shown permits coupling collars such as shown at 72 to be readily passed 80 through the casing head and spider, as it will be noted that the annular opening of the spider and casing head flange 13 is the same. This is a feature of great importance in this invention, as it often occurs that excessive pressure may tend to lift the tubing from the well and the moment any indication of trouble of this kind arises, it is only necessary to drop the slips 7 in position to hold the tubing, and then compress the packing *d*. Furthermore, the tubing may be passed downwardly within the casing and the slips 7 placed within the spider at any time desired, the packing at all times being ready for instant application to the periphery of the tubing to prevent loss of fluid or gas as between the casing and tubing. Figure 1 shows the general arrangement and application of the device, it being intended that the same may be placed in the cellar 100 beneath an oil well derrick.

Particular attention is directed to the fact that inward movement of the wedge rings compresses the packing in all directions; that is to say, the packing is forced through the slotted portions 40 and at the same time closely wedged about the tubing 8 and against the guides 20 and 21. This is accomplished in part by the general shape of the compressors and likewise by the form of the 110 upper and lower split annular discs 24, 25, 26 and 27. It will be remembered that the discs are enlarged at the portions 30 and 31 and when pressure is exerted at the periphery of such packing means *d*, the 115 tendency would be to force the upper and lower surfaces thereof outwardly. This method of constructing the top and bottom plate members provides a three-way pressure for the packing when the compressors 120 are moved to compress such packing.

It is obvious that various changes and modifications may be made in practicing the invention, in departure from the specific showing of the drawing, without departing 125 from the true spirit of the invention.

Having thus disclosed my invention, I claim and desire to secure by Letters Patent:

1. In a device of the character disclosed, 130

a casing head formed with an enclosure, 5 packing means formed of flexible material and constituting a split annulus within said enclosure, upper and lower slotted discs for said packing means, said upper and lower discs enclosing the said packing means, and further means received between said discs and adapted to bear against the periphery of said packing means to compress the same 10 to in part force the packing means through the slotted portions of the discs into engagement with the casing head.

2. In a device of the character disclosed, a casing head, two discs spaced apart, and a 15 packing means between the said discs; said discs being formed with rim flanges, wedge rings confined between the said discs and said rim flanges, and said packing means being peripherally grooved for reception of said

wedge rings, in combination with means for 20 moving said wedge rings to compress the packing.

3. In a device of the character disclosed, a casing head, a spider associated therewith, said spider and casing head being so related 25 as to provide an enclosure, upper and lower annular discs within said enclosure, flexible packing means between said upper and lower discs, and packing means interposed between the said discs and the said spider and casing 30 head, and means adapted to compress the flexible packing means between the said discs to cause the said upper and lower discs to tightly engage the packing means between said discs, the spider and casing head. 35

In testimony whereof, I have signed my name to this specification.

JOHN BERGSTEN.
